UNITED STATES PATENT OFFICE.

STEPHEN N. EISLER, OF NEW ORLEANS, LOUISIANA, ASSIGNOR OF ONE-HALF
TO SHAKSPEARE & SWOOP AND JOHN D. BELTON, OF SAME PLACE.

ROTARY PUMP.

SPECIFICATION forming part of Letters Patent No. 513,901, dated January 30, 1894.

Application filed August 3, 1893. Serial No. 482,259. (No model.)

To all whom it may concern:

Be it known that I, STEPHEN N. EISLER, a citizen of the United States, residing at New Orleans, in the parish of Orleans and State of 5 Louisiana, have invented new and useful Improvements in Rotary Pumps, of which the following is a specification.

This invention has for its object to provide a new and improved apparatus for raising 10 water or other liquid by the action of a pair of rotary wheels having blades or vanes so relatively arranged that while the wheels revolve in unison in one direction they operate to force the liquid in opposite directions, one 15 wheel forcing the water directly upward therefrom, and the other wheel forcing the water downward into lateral passage ways in which the water rises to the desired point of elevation.

20 To accomplish this object my invention consists in the features of construction and the combination or arrangement of parts hereinafter described and claimed, reference being made to the accompanying drawings, in 25 which—

Figure 1 is a vertical sectional view of a water raising apparatus embodying my invention. Fig. 2 is a horizontal sectional view taken on the line 2—2, Fig. 1. Fig. 3 is a horizontal sectional view taken on the line 3—3, Fig. 1; and Fig. 4 is a detail vertical sectional view taken on the line 4—4, Fig. 1.

In order to enable those skilled in the art to make and use my invention, I will now 35 describe the same in detail, referring to the drawings, wherein—

The numeral 1 indicates an external casing which is square, or similarly shaped in cross section, as will be understood by reference to 40 Figs. 2 and 3. The casing is supported at each corner by an upright or post 5, and to each pair of posts is secured a vertical wall or partition 6, one of which is located directly opposite the other, as shown in Fig. 2, for the 45 purpose of forming a central vertical chamber 7, and two lateral vertical or side chambers 8, which chambers 7 and 8 rise to any desired point of elevation. The lower end 50 portions of the walls or partitions 6 are recessed to provide the ports or passages 9, Figs.

1 and 3, to place the lower end of the central chamber 7 in communication with the lateral or side chambers 8, and the lower end portion of the external casing is provided in opposite sides with lateral inlet ports or orifices 10 and 55 12 which are respectively located above and below a fixed horizontal diaphragm or partition 13, through which extends a vertical shaft 14 supported at its lower end in a step 15, and adapted to be revolved through the 60 medium of any suitable driving mechanism. As here shown, the upper end portion of the shaft is provided with a band pulley 16 by which to rotate it, but obviously other mechanical devices for this purpose may be employed. 65

The casing is provided at its lower portion with an inwardly projecting shoulder or ledge 17, arranged beneath the diaphragm or partition 13, and with a similar shoulder or ledge 70 18, arranged above the diaphragm or partition 13. The lower shoulder or ledge 17 supports the lateral flange 19 of a metallic circular collar 20, and the upper shoulder or ledge 18 supports the flange 21 of a similar 75 circular metallic collar 22.

In the two collars 20 and 22 are arranged two rotary wheels 23 and 24 having their radial blades or vanes 25 and 26 inclined in reverse directions in such manner that water or 80 other liquid entering the port or orifice 12 is forced downward by the wheel 23, and water or other liquid entering the port or orifice 10 is forced directly upward by the wheel 24. The water or liquid which is forced downward 85 by the wheel 23 passes laterally through the recesses or ports 9 into the vertical side chambers 8, and by the means described the water or liquid is caused to rise or ascend in the central chamber 7, as well as in the side 90 chambers 8.

The diaphragm or partition 13 is provided at its center with a suitable bearing 27 for the shaft 14, and the upper end portions of the posts 5 are provided with cross pieces 28 and 95 29 which support bearings 30 and 31 for the shaft, which bearings are located respectively above and below the band pulley 16.

The shaft 14 is provided with lower and upper adjustable collars 32 and 33, adapted to 100

bear respectively against the bearings 30 and 31, for the purpose of preventing undue vertical movements of the shaft 14.

The wheels 23 and 24 are provided with collars and set screws, as at 34 and 35, Fig. 1, for the purpose of adjusting the wheels on the shaft 14 with relation to the circular metallic collars 20 and 22.

The pump described and shown is particularly designed for removing water from ditches and discharging the same over embankments into rivers or other places, and for this purpose the base portion of the pump is arranged in the ditch, so that the water therefrom can enter through the ports or passages 12 and 10.

Having thus described my invention, what I claim is—

1. The combination of a casing containing a vertical chamber 7 having an inlet at its base portion and vertical lateral chambers 8 having inlets at their base portions, a vertical rotary shaft extending through the central chamber, a pair of wheels 23 and 24 fixed to the shaft and arranged one above the other, the upper wheel having radial blades for forcing liquid upward in the central chamber, and the lower wheel having radial blades for forcing liquid upward through the lateral chambers, and the diaphragm 13 interposed between the two wheels and closing communication between the lower end of the vertical chamber and the lower ends of the lateral chambers, substantially as described.

2. The combination of a casing having a vertical central chamber 7 provided with an inlet at its base portion and vertical lateral chambers provided with inlets at their base portions, a vertical rotary shaft extending through the central chamber, upper and lower annular collars 20 and 23, two wheels 23 and 24 fixed to the vertical shaft and rotating respectively in the annular collars, and a diaphragm 13 interposed between the two wheels and closing communication between the lower end of the central chamber and the lateral ends of the lateral chambers, substantially as described.

3. The combination of a casing having a vertical central chamber 7 provided with an inlet at its base portion and vertical lateral chambers provided with inlets at their base portions, a vertical rotary shaft extending through the central chamber, upper and lower annular collars 20 and 23, two wheels 23 and 24 fixed to the vertical shaft and rotating respectively in the annular collars, and a diaphragm 13 interposed between the two wheels and closing communication between the lower end of the central chamber and the lateral ends of the lateral chambers, substantially as described.

In testimony whereof I have hereunto set my hand in presence of two subscribing witnesses.

STEPHEN N. EISLER.
